BRUSH CONSTRUCTION

Anthony Ozdobinski, Edwardsville, Pa.

Application March 1, 1950, Serial No. 146,950.

1 Claim. (Cl. 15—226)

1

This invention relates to brush constructions. It is an object of the present invention to provide brushes of a type which can be formed by a wrapping and folding of a strip about a handle in any easy manner and bearing brush projections serving to effect the brushing operation of the brush and wherein these brush projections are connected to a continuous strip which is wrapped about the handle.

It is another object of the present invention to provide a brush construction formed by a wrapping operation wherein the turns of the brush strip can be held in place by a simple application of heat to the material whereby the several turns will be permanently fixed together, the brush strip material being formed of acetate film or the like which, upon the application of heat, causes adhesion of the turns or joined layers of the material.

Other objects of the present invention are to provide a brush construction which is simple, inexpensive to manufacture, does not require the use of attaching elements for the connection of the material with the handle, has a minimum number of parts, washable and will not permit hard particles to collect within the brush, and efficient in operation.

For other objects and for a better understanding of the invention, reference may be had to the following detailed description taken in connection with the accompanying drawing, in which:

Fig. 1 is a perspective view of a brush having two forms of wrapping of the brush material upon the handle, the brush being of double ended construction.

Fig. 2 is a perspective view of the strip material used on one end of the brush.

Fig. 3 is a perspective view of the strip material used on another end of the brush and illustrating the manner in which the strip material is applied to the end of the brush handle.

Fig. 4 is a perspective view of another form of brush utilizing a wire handle.

Fig. 5 is a perspective view illustrating the method by which the brush of Fig. 4 is formed.

Fig. 6 is a perspective view of still another form of brush.

Fig. 7 is a perspective view of the strip material before it is applied to the handle of the brush shown in Fig. 6.

Fig. 8 is a fragmentary sectional view of the brush shown in Fig. 6 taken on line 8—8 thereof.

Fig. 9 is a side face view of still a further form of brush.

Fig. 10 is a side edge of the brush shown in Fig. 9.

2

Referring now particularly to Figs. 1, 2 and 3, there is shown one form of brush constructed according to one method. There is shown a handle 10 having brush formations 11 and 12 on the respective opposite ends of the same. The brush formation 11 is constructed from a folded and double strip 13 shown in Fig. 2. This strip is folded, as indicated at 14, and slits 15 are made therein to form brush projections 16 of double formation. The strip, when folded, is tapered in shape. The length of the slits 15 are preferably uniform, although they can be made of varying length. This strip material is preferably made of an acetate film or of similar synthetic material which will give or stretch to a certain extent as it is wrapped upon the handle 10. Starting with the large end of the strip 13, it is wound upon the handle and the lower edge is kept uniform throughout so that a brush formation of varying layers resulting from each turn is had. When the entire strip has been wound upon the handle 10, it can be made secure by a tack 17, but upon the application of heat to the ends of the turns, the material will become a solid mass and made substantially integral with the handle. By using the tapered strip 13, the projections 16 will be longitudinally spaced along the brush.

If a uniform width strip 18, such as shown in Fig. 3, is used, the brush formation 12 will be provided. This strip 18 is folded and slit at 19 to provide projections 20 of uniform length. The slits are of the same length and the material is wound upon the handle in the same manner as above described and after the end of the strip is reached it can be made secure upon the handle by the application of heat to the ends of the turns and as indicated at 21 whereby to form an integral mass and to make secure the strip upon the handle 10.

In Figs. 4 and 5, there is shown a still further form of the invention wherein the strip from which the brush formation, as indicated at 23, is formed is of single thickness and slit from one edge, as indicated at 24, to provide a plurality of brush projections 25. A twisted wire handle 26 having an end loop 27 is placed on the material, as shown in Fig. 5, and the material is wound on the end of the handle whereby to form the brush formation 28, Fig. 4. Once the strip 23 is in place and the brush formation 28 is formed, the same is made secure upon the handle by the application of heat to cause the layers of the material to adhere to one another and thereby prevent the same from becoming loose. This material, when placed or wound upon the handle,

is stretched a slight amount so there is a very tight grip or winding of the material so that readily upon the application of heat the solid mass is formed. The material is of any chemical structure which readily becomes molten upon the application of heat to cause the intermingling of the chemical molecules with one another to provide an integral mass. Only slight heat is required and the securing can be effected only at the ends of the turns and not necessarily throughout the length of the strip to any great extent.

Referring now particularly to Figs. 6, 7 and 8, there is shown a still further form of the invention wherein a strip 31 is of wide formation throughout a part of its length, as indicated at 32, and this wide formation is doubled upon itself whereby to provide folded bristles or projections 33 adjacent slits 34. These slits are of uniform length and likewise the projections 33 will be of the same length. The strip is provided with a tail portion 35. The doubled portion 32 is first wound upon the end of stick 36 whereby to provide a brush formation 37 and by the application of heat, this double portion can be made 25 secure in place. Thereafter, the tail portion 35 is wound in an overlapping manner, as shown in Figs. 6 and 8, to cover the handle 36 with a wrapped sleeve formation 38 serving to cover the handle and if the material is colored, the handle will have a pleasing appearance.

Referring now to Figs. 9 and 10, there is shown a slightly different form of the invention wherein there is provided a plurality of layers 41, each of which having slits 42 with projections 43 to form the brush part of the structure. These layers are stacked one upon the other and by the use of a hot rod applied at the locations indicated at 44, notches are made in the material and the edges of the material are secured together. This material being of acetate film or the like, the application of heat readily welds the layers of the material together.

It should now be apparent that there has been provided a brush construction wherein layers of the sheet material are formed and upon the application of heat to the layers a solid handle mass is formed leaving the brush projections formed by a slitting of the material free to be flexed and used.

While various changes may be made in the detail construction, it shall be understood that such changes shall be within the spirit and scope of the present invention as defined by the appended claim.

I claim:

A brush construction comprising an elongated handle, a strip of flexible sheet material having a folded portion and a tail portion, said folded portion being slit throughout the fold to provide loop bristles throughout a part of its width and providing for an unslit part, said folded portion being wound upon the end of the handle by its unslit part and the tail portion being wound with over-lapping turns along the length of the handle whereby to provide a gripping layer thereupon.

ANTHONY OZDOBINSKI.
